[57] ABSTRACT

A latch device which may simultaneously act as a hinge having a master latch and at least one slave latch. Each latch includes a pair of cooperating members attached to separate wall members which, when engaged, present a series of bores in an axially aligned configuration. By turning a threaded member housed in the master latch an actuator bar may be moved thereby causing a series of tapered pins fixedly connected to the actuator bar to move into the axially aligned bores. The contour of the cooperating latch members enable the latches to act as hinges; i.e., to pivot about the tapered pins.

FIG. 5

LATCH AND HINGE DEVICE

BACKGROUND OF THE INVENTION

This invention relates generally to latching devices and more particularly to a latch system which permits relative pivotal movement between the latched members.

It has frequently been found either desirable or necessary to fix a pair of wall members with respect to each other along their respective edges. For example, in the case of a cylindrical container having a portion of its wall surface removable therefrom thereby providing an opening for easy access to the inside of the container, it became necessary to employ a device for securely fastening that removable portion of the wall surface; i.e., the "access member" back in position in continuity with the cylindrical surface of the container. Such a device must provide both a positive locking function along the mating surfaces of the walls of the container and the access member and, in addition, make for a quick and facile accessibility to the inside of the container.

In the past, several diverse arrangements have been utilized to satisfy such requirements. Most commonly, a plurality of fixed, discrete, hinge devices were positioned along one edge of the opening which cooperated with the access member and the container wall to allow pivotal movement therebetween. The opposite edge of the access member usually had a latch positioned thereon, such, for example, as a conventional pivotal hook type fastener, which, when moved into position over a stud in the container wall, prevented the access member from inadvertently swinging open.

In many instances, however, it has been found desirable to have the access member entirely removable from the opening. For example, the servicing of electrical equipment which may be positioned within the container requires a maximum of available working space around the opening and very often the hinged access member provided an obstacle to easy maintenance of such equipment. Obviously, it is not feasible using the apparatus previously discussed to accomplish a secure closure between the two surfaces while providing either a pivotally openable access member and, in addition, a completely removable access member.

SUMMARY OF THE INVENTION

Accordingly, one object of this invention is to provide a new and improved latching device.

Another object of the instant invention is the provision of a new and improved latching system which may positively secure one member to another member.

Still another object of the present invention is to provide a new and improved latching system which permits pivotal movement between latched members.

A further object of this invention is the provision of a latching system which enables quick and facile unlatching.

Briefly, in accordance with one embodiment of this invention, these and other objects are attained by providing a master latch and at least one slave latch positioned in a line therewith on the members desired to be latched. The slave latches are coupled to the master latch and to each other by a common actuator bar, the movement of which selectively engages or disengages the latch components thereby locking or unlocking the members.

BRIEF DESCRIPTION OF THE DRAWING

A more complete appreciation of the invention and many of the attendant advantages thereof will be readily appreciated as the same becomes better understood by reference to the following detailed description when considered in connection with the accompanying drawings wherein:

FIG. 1 is a partial plan view of the overall latching system in an unpivoted condition according to the present invention;

FIG. 2 is a front sectional view taken along line 2-2 of FIG. 1;

FIG. 3 is a front sectional view of the present invention taken along line 3-3 of FIG. 1;

FIG. 4 is a front view of the latching system in a pivotal mode; and

FIG. 5 is a perspective view of an application of the latching to a cylindrical container.

DESCRIPTION OF THE PREFERRED EMBODIMENTS

Referring now to the drawings wherein like reference characters designate identical or corresponding parts throughout the several views, and more particularly to FIGS. 1 and 2 thereof, the latching and hinge system of the present invention is shown as including a master latch 10 and a plurality of slave latches 12 (only one of which is shown) cooperating with a rectangular actuator bar 14 in a manner which will be more fully described hereinafter.

Because of the great similarity between the slave latch 12 and the master latch 10, parts on the slave latch will be denoted by the same numerals primed as the corresponding parts of the master latch. The master latch 10 includes first and second similarly shaped latch members 16 and 18 fixed by conventional means, such for example, as rivets 20, to the external surfaces 22 and 24 of two walls 25 and 27 of a container having edges nearly abutting at 26. Each latch member includes a rigid base plate 28 of a generally rectangular shape whose under surface 30 is formed to conform with the surface of the wall to which it is to be attached.

Formed centrally and extending transversely across base plates 28 of latch members 16 and 18 are male latching portion 32 and female latching portion 34, respectively. Each latching portion includes flange members 38 and 40 of gradually increasing perpendicular height adjacent extremities 42 and 44, respectively, of which are cantilevered over frontal edges 36 of base plates 28. Extremity 42 of male latching portion 32 includes a projection 45 having a smooth circular bore 46 formed therethrough and further having an arcuate-shaped edge 48. Extremity 44 of the female latching portion 34 comprises two projections 50 and 52 which define an intermediate recess 54 adapted to receive male projection 45. Projections 50 and 52 each have formed therethrough a smooth circular bore 56 and each projection has an arcuate shaped edge 58 similar to the edge 48 of male projection 45. Further, a second smooth circular bore 60 is formed through female extremity 44 of the master latch 10 on an axis parallel to the axis of bores 56.

The slave latch 12 is of the same general configuration as the master latch 10, the only difference therebetween being that the female extremity 44' of female flange member 40' does not have a bore corresponding to bore 60 of female flange member 40.

As shown in FIGS. 1 and 2 the relative positioning of the latch members is such that when the walls of the container are in the unpivoted position shown in FIG. 2, i.e. the edges of the walls 25 and 27 are proximate but not abutting as at 26, the male projection 45 of latch member 16 is seated within the recess 54 on latch member 18. When in this position, it is further to be noted that the bore 46 is axially aligned with the bores 56. The positioning of base plates 28 on their respective wall surface are such that the edge 36 of base portion 28 of the latch member 18 is at a greater distance from the point of rear abutment 26 of the edges of the walls 25 and 27 than the edge 36 of base portion 28 of the latch member 16. This particular positioning provides room for the actuator bar 14 to be seated between the edge 36 of latch member 18 and abutting edges 26.

As clearly shown in FIG. 1, the slave latch 12 is located on the surfaces 22 and 24 in the same manner as the master latch 10 and, further, the componential latch members 16' and 18' are positioned with respect to themselves in the same fashion as the master latch 10. Due to this positioning, the bores 46', 50' and 52', in addition to being axially aligned with each other are also axially aligned with the corresponding bores 46, 50 and 52 in the master latch 10.

The actuator bar 14 is positioned adjacent and parallel to the edges 36 and 36' of body portions 18 and 18' below the cantilevered right flange member extremities 44 and 44'. Bar 14 is prevented from deflecting in a direction perpendicular to the cylindrical surfaces 22 and 24 by clearance slots 61 (of which is shown in FIG. 1) formed in the bar 14 provided midway between adjacent master-slave latches which cooperate with conventional fasteners 62 connected to the wall 27 having enlarged head portions 65 which restrain and fasten the bar 14 to the container wall. Slots 61 are elongated in the direction of the axis of the bores in the latch projections to permit movement of the bar 14 in a direction parallel thereto and in a manner to be described presently.

Adjacent each master and slave latch and fixed to the bar 14 by conventional means, such for example, as by welds 63 (FIG. 3) are substantially cube-shaped blocks 64. Each block 64 contains a through bore 68 axially aligned with the bores 50, 45 and 52 which fixedly houses an elongate pin 66. The block 64 adjacent the master latch 10 further includes a threaded bore 80 formed therethrough which is axially aligned with bore 60 of the female extremity 44. Pin 66 includes an offset taper 70 on its free end (FIG. 1) and has a circular cross-section for reasons which will become clearer. When projection 45 is seated within recess 54 the pin 66 may be positioned within the aligned bores 50, 45 and 52. The tapered end 70 of the pin serves to correct any slight misalignment of bores as it is passed therethrough. When pins 66 are positioned within the bores in the respective latches, the latches may be said to be in an engaged condition.

In order to disengage the latches, the pins 66 must be withdrawn from the bores within which they are positioned during latch engagement. This is accomplished by turning an elongate partially threaded cylindrical member 72 having an enlarged head portion 73 to facilitate the turning thereof rotatably positioned within the smooth bore 60 in latch member 18 of master latch 10. The cylindrical member 72 includes a smooth portion 74 which is retained within bore 60 by a circular lock nut member 76 fixed to the cylindrical member 72 adjacent and abutting an edge of the female latching portion 34 and a threaded shank portion 78 which extends beyond the lock nut member 76 and cooperates with the threaded through bore 80 in block 64 adjacent the master latch 10. Upon rotating the socket head member 72 in one direction a predetermined number of turns, the block 64 is caused to move away from master latch 10 and concomitantly causes the actuator bar 14 to move thereby withdrawing pins 66 from their respective latch bores and effecting disengagement of the latches. Conversely, rotating the cylindrical member 72 in the opposite direction causes the actuator bar 14 to be drawn toward the master latch 10 thereby allowing the pins 66 to be positioned within their associated latch bores thereby effecting engagement of the latches.

Referring now to FIG. 4 wherein the latch system is shown in its engaged mode, the wall 25 may be considered as an "access member" to gain entry within a container. Since pins 66 are circular in cross-section, they may serve, when the latches are engaged, as hinge pins to allow the wall 25 to be pivotally rotated relative to wall 27 of the container. The arcuate-shaped edges 48 of projection 45 assure no interference of

that projection with the actuator bar 14. Similarly, should it be desired to rotate wall 27 in lieu of the wall 25, the arcuate edge 58 would also assure the absence of any interference. It is therefore seen that both a latching and hinge function is provided by the latching mechanism of the present invention.

The latch members may be fabricated as a forging with each half of each latch made from a common forging. The differences in configuration can be machined thereby providing a better mating of the two halves.

Referring to FIG. 5 wherein a cylindrical container 82 having an access plate 84 latched to the container wall 86 by two rows of latches 88 and 90 of the present invention. Should it be desired to open the access member 84, it is only necessary to disengage one line of latches, say line 88, and then pivotally rotate the plate 84 about the other line 90. If it is found to be necessary to remove the access plate completely from the container, it is merely required to disengage the line of latches 90 and lift the member 84 out.

Obviously, numerous modifications and variations of the present invention are possible in light of the above teachings. It is therefore to be understood that within the scope of the appended claims, the invention may be practiced otherwise than as specifically described herein.

What is claimed as new and desired to be secured by Letters Patent of the United States is:

1. A latch and hinge device for latching two wall members comprising:

a master latch and at least one slave latch, each of said latches including a first base member connected to a first wall member and a second base member connected to a second wall member, each of said base members having overlyingly fixed thereto a latching portion including at least one projection having a bore formed therein, said bores adapted to be axially aligned upon engagement of said base members;

said first base member connected to the first wall member so that said projection formed thereon does not extend over the end edge of said first wall member and said second base member connected to said second wall member so that said projection formed thereon extends beyond the edge of second wall member;

latch engaging means including an elongate bar slideably mounted on said first wall member substantially between said first wall member and said projections formed on said first base member, said elongate bar having at least two spaced rod members fixed to blocks attached to said bar in substantial adjacent relationship to said latches, said rods receivable within said axially aligned bores; and means for actuating said engaging means including an elongate cylindrical member having a smooth portion and a threaded portion, said smooth portion rotatably positioned within an aperture formed in said projection formed on said first base member of said master latch, and said threaded portion received in a threaded bore formed in the block member in adjacent relationship to said master latch, whereby rotation of said elongate cylindrical member effects the sliding of said bar relative to said projection to insert said rods into said aligned bores.
